UNITED STATES PATENT OFFICE.

EUGENE HENRY GIBBS, OF LUDLOW, VERMONT, ASSIGNOR TO THE LUDLOW
TOY MANUFACTURING COMPANY, OF SAME PLACE.

DRAW-IRON FOR WAGONS.

SPECIFICATION forming part of Letters Patent No. 337,393, dated March 9, 1886.

Application filed October 2, 1885. Serial No. 173,796. (No model.)

To all whom it may concern:

Be it known that I, EUGENE HENRY GIBBS, of Ludlow, Windsor county, Vermont, have invented a certain new and useful Improvement in Draw-Irons for Small Wagons like Boys' Express-Wagons, &c., of which the following is a specification.

This invention is designed to provide a simple and effective connection between the handle and the axle or body of a wagon of the kind referred to in the preceding paragraph, a connection which will permit the handle to be readily removed whenever desired, but which at the same time will forbid its removal so long as the wagon is in its natural or normal position.

To this end the invention consists in providing the body or axle of the wagon with irons, termed for convenience sake "axle-irons," provided each with a hole or bearing and with a slot communicating therewith, but of a width less than the diameter of the hole or bearing, and in combining with said axle-irons what may be termed a "draw-iron"—that is to say, a metallic piece to which the tongue or handle is attached—said draw-iron being provided at its rear end with laterally-extending journals to enter the bearings in the axle-irons, and with radial fins or lugs on the outer ends of said journals which must pass through the slots in the axle-irons before the journals can enter to proper place in their bearings. The fins or lugs and the slots are so placed with respect to one another that the handle must be brought to a position at about right angles with the body of the wagon before they (the lugs and slots) will register; and it is preferred to thus locate them in such manner that they can be brought into register only by lowering the handle—or, in other words, by raising the wagon from the ground. This insures the engagement of the draw-iron with the axle-irons so long as the wagon rests on the ground in its natural position; and in order to effect the disengagement of the two requires that the wagon should first be lifted from the ground a distance sufficient to allow the tongue to drop to vertical or approximately vertical position.

The nature of the invention and the manner in which the same is or may be carried into

effect will be readily understood by reference to the accompanying drawings, in which—

Figure 1 is a perspective view of a boy's express-wagon embodying my invention. Fig. 2 is a perspective view of the draw-iron detached. Fig. 3 is a side elevation of the front portion of the wagon and the handle in the position which they assume with respect to one another when the draw-iron is in position to be disengaged from the axle-irons.

From the front of the front axle of the wagon project two axle-irons, A, formed each with a hole, a, and with a horizontal slot, b, which communicates with and extends back from the rear of the hole. The holes are the bearings for the journals of the draw-iron hereinbefore referred to, and the slots are to permit the passage of the fins or lugs on said journals.

The draw-iron is shown at B. It is provided at front with a central extension or tongue recessed on its under side for the reception of the wooden handle C, and having holes through which pass the screws by which the handle is held to the draw-iron. At the rear of the draw-iron is a cross-bar, the laterally-projecting and cylindrical ends c of which form journals to fit the holes or bearings a in the axle-irons; and these journals are provided each with a radial fin or lug, d. The cross-bar is of such length that its journals c will project through and beyond the axle-irons when the draw-iron is in place, and the lugs d are such distance apart from one another that when the draw-iron is thus placed they will come just outside of the axle-irons and so prevent end play of the journals in the axle-irons so long as the lugs are not in register with the slots b. The journals c themselves are of such length that when one of them is inserted to its full length into and through its bearing in one of the angle-irons, the outer end of the other one will come just inside of the opposite axle-iron. Finally, the slots b, as above said, are horizontal, and the lugs d are so placed that when the handle or draw iron is in place and held horizontally or in line with the wagon they will extend downward vertically or at about right angles to the slots b, as indicated in Fig. 1.

The manner of fitting the draw-iron to and removing it from the axle of the wagon will be

apparent from the foregoing description, and does not require detailed explanation.

- When the two are fitted together, as seen in Fig. 1, it is manifest that so long as the wagon 5 rests on the ground in its natural position the handle cannot be brought to a position in which the lugs will register with the slots. To bring about the result last named, the wagon or its front axle must be raised far enough to permit 10 the handle to drop to the position indicated in Fig. 3. When the parts are brought to that position, it is easy by a lateral movement to disengage and remove the draw-iron from the wagon.
- 15 I have hereinbefore indicated that my improvement is designed more particularly with reference to the needs of small vehicles—such as boys' express-wagons, &c. The method of connection or attachment which I have invented is, however, applicable also to wagons as well as sleighs of other kinds, and I desire to be understood as including this application in my claim.
- It will also be noted that by reason of the 25 construction and arrangement of parts the body of the draw-iron does not project laterally beyond the axle-irons, and that the lugs alone serve to prevent end-play of the draw-iron in its bearings.
- 30 I do not claim, broadly, the combination of journal-irons provided with lugs, with coupling-irons formed with bearings and communicating-slots; but,

Having now described the invention and the manner in which the same is or may be carried into effect, what is claimed as new is as follows:

1. The axle-irons formed with lateral openings or bearings and communicating-slots, as described, in combination with the draw-iron formed with laterally and outwardly-extending end journals and lugs adapted to pass endwise through said bearings and slots, said lugs being placed at such distance apart that when the journals are in place in the bearings the 45 lugs shall be on the exterior opposite faces of the axle-irons, as and for the purposes hereinbefore set forth.

2. The combination of the wagon-body, the axle-irons provided with bearings and communicating-slots, the tongue or handle, and the draw-iron provided with laterally and outwardly extending journals to enter said bearings, and with lugs to pass through said slots placed at such distance apart that when the 50 draw-iron is in place they shall embrace between them the axle-irons, substantially as and for the purposes hereinbefore set forth.

In testimony whereof I have hereunto set my hand this 28th day of September, 1885.

EUGENE HENRY GIBBS.
